CLAIM

Aug. 5, 2016 (CA) 169787

We claim the ornamental design for a portable sawmill upper carriage front, as shown and described.

(51) **LOC (11) Cl.** **15-09**

DESCRIPTION

(52) **U.S. Cl.**

FIG. 1 is a top front perspective view of a portable sawmill upper carriage front showing the design thereof;

USPC **D15/134**

FIG. 2 is a top rear perspective view of the design shown in FIG. 1;

(58) **Field of Classification Search**

FIG. 3 is a front elevation view of the design shown in FIG. 1;

USPC D15/127, 133, 134, 138, 199

FIG. 4 is a back elevation view of the design shown in FIG. 1;

CPC B23D 55/02; B27B 15/02; Y10T 83/68;

Y10T 83/95; Y10T 83/707; Y10T 83/722;

Y10T 83/7101; Y10T 83/7763

FIG. 5 is a left side elevation view of the design shown in FIG. 1;

See application file for complete search history.

FIG. 6 is right side elevation view of the design shown in FIG. 1;

(56) **References Cited**

FIG. 7 is top plan view of the design shown in FIG. 1; and,

U.S. PATENT DOCUMENTS

FIG. 8 is bottom plan view of the design shown in FIG. 1. The broken lines in the drawings depict unclaimed environmental subject matter.
